The ornamental design for a shoe sole, as shown and described.

DESCRIPTION

FIG. 1 is a right side elevational view of a shoe sole showing my new design in a position of use;
FIG. 2 is a left side elevational view of the sole unmounted;

FIG. 3 is a bottom plan view thereof;

FIG. 4 is a right side elevational view thereof;

FIG. 5 is a top plan view thereof;

FIG. 6 is a front elevational thereof; and,

FIG. 7 is a rear elevational view thereof.

The broken line showing of a shoe upper in FIG. 1 is for illustrative purposes only and forms no part of the claimed design.
